FLASHING

William A. Fingles, Jr., Baltimore, Md., assignor
to The Cheney Company, Winchester, Mass., a
corporation of Massachusetts

Application July 19, 1932, Serial No. 623,441

7 Claims. (Cl. 72—127)

The present invention relates generically to flashing. More particularly, the invention has particular relation to that type of wall flashing which is adapted to be embedded, in sheet form, 5 in the mortar between the courses of brick of the wall and which is provided with deformations, such as ribs and projections, adapted to interlock and key the mortar above the sheet of flashing to that therebeneath, as well as to prevent relative movement between the mortar and the flashing in any direction.

A primary object of the invention is the provision of a novel form of flashing of the character above outlined which shall be capable of inexpensive manufacture but which shall nevertheless be highly efficient in effecting its intended functions.

A further object of the invention is to provide a particular and novel relationship between the several sets of deformations of the flashing sheet whereby one set thereof shall act, in addition to carrying out its own intended peculiar function, to protect the other set of deformations from injury, whereby the latter is positively enabled to 25 perform the predetermined task assigned thereto.

To this end, the flashing according to the present invention comprises essentially a suitable sheet or strip of metal, such as copper, which is provided with one set of deformations in the form 30 of a plurality of spaced transversely extending overhanging ribs which may be substantially Z- or S-shaped in cross-section.

The peculiar configuration of these ribs provides reentrant recesses in which mortar is adapted 35 to be lodged when the strip of flashing is embedded in a layer thereof so that the mortar above the flashing is in effect interlocked with that therebeneath. In this way, the bond between the mortar on each side of the flashing is not 40 broken, as would be the case with ordinary flat sheet metal flashing. In addition, the ribs also prevent relative longitudinal movement between the mortar and flashing.

To prevent relative movement between the 45 mortar and the flashing transversely of the latter, the strip is provided with a second set of deformations in the form of a plurality of series of projections extending upwardly from the body of the metal intermediate the first set of deformations. These projections, which may be of any 50 suitable configuration, provide downwardly opening recesses or pockets into which the mortar is adapted to extend, whereby relative transverse 55 movement of the flashing is prevented.

When the strip of flashing is embedded in the 60 layer of mortar on which the relatively heavy coping block of the wall is placed, this block, finding inadequate support on the soft freshly-laid mortar, bears down upon the sheet of flash-

ing, crushing or flattening the S- or Z-shaped ribs thereof, eliminating the reentrant recesses formed thereby, and consequently destroying the interlocking and keying character of the flashing.

To prevent such undesired mashing of this one set of deformations—the ribs—the other set—the projections—are disposed relatively closely adjacent to the ribs and are formed so that they (or portions thereof) extend upwardly to a point, appreciably beyond the tops of the ribs. Due to 10 their shape, these projections are structurally much stronger than the ribs and can easily support considerable weight without being mashed or crushed. The coping block is therefore adequately supported by these projections, out of 15 contact with the ribs, while the mortar hardens.

It is thus evident that the projections provided according to this invention exercise dual functions, first, to prevent relative movement between the mortar and flashing and, secondly, to protect the transversely-extending ribs against 20 crushing forces.

On the accompanying sheet of drawing, wherein the invention is illustratively set forth,—

Fig. 1 is a top plan view of a portion of the sheet 25 of flashing according to one embodiment of the present invention;

Fig. 2 is a sectional view through the coping block and top brick course of a masonry wall showing the flashing of Fig. 1 embedded in the 30 layer of mortar therebetween, the sectional view of the flashing corresponding to line 2—2 of Fig. 1;

Fig. 3 is a sectional view taken on line 3—3 of 35 Fig. 1.

Similar reference characters refer to corresponding parts throughout the several figures of drawing.

Referring now to the drawing, reference numeral 10 designates broadly a sheet of flashing fabricated from suitable sheet metal, preferably copper. In the embodiment of the invention illustrated in Figs. 1 and 2, the sheet of flashing is provided with a plurality of spaced ribs 11 extending transversely thereacross and with a plurality of sets of upwardly extending projections 13, 14 and 15, preferably arranged as clearly shown in Fig. 1.

Transverse ribs 11, as reference particularly to Fig. 2 of the drawing will show, are substantially 50 Z-shaped in cross section, so that the flashing consists essentially (see Fig. 3) of a plurality of relatively long parallel inclined areas (from which the projections 13, 14, 15 and the like may be displaced) connected by a plurality of oppositely inclined relatively short areas.

The material adjacent the edges of the long areas and the short areas define the Z. The latter each forms a pair of reentrant recesses 16, as shown, adapted to receive mortar 17, and 55

thereby keys the mortar above the flashing (Fig. 2) with that therebelow. It is apparent that by reversing the relative inclination of the parts, the ribs 11 will be substantially S- instead of Z-shaped in cross section. In either case, a longitudinal section through the flashing along a line, such as 3—3 of Fig. 1, will be substantially saw-tooth shaped (see Fig. 3). The ribs 11 also prevent relative longitudinal movement between the flashing and the mortar.

10 Projections 13, 14 and 15 comprise areas or portions of the metal flashing displaced therefrom and connected thereto by endless inclined walls, as is clearly shown in Figs. 1 and 2. The latter figure of drawing further illustrates the vertical extent of the projections, and particularly projections 15, with respect to the top of the easily flattened Z-shaped ribs 11. If the weight of the coping block 18 is too much for the soft freshly-laid mortar, the ribs 11 will nevertheless not be crushed by the block since the latter will be supported by the protruding projections, the structural form of which enables them adequately to support the weight of the coping block 18. In addition to this protective function, the projections 13, 14 and 15 also prevent relative horizontal movement in any direction of the flashing with respect to a cooperating layer of mortar (such as layer 17, between coping block 18 and the course of bricks 19 of a brick wall).

15 Although a single embodiment of the present invention has been disclosed in detail, numerous changes may be made in the constructions without departing from the spirit of the invention. The invention is therefore not intended to be limited by the foregoing specific disclosure nor otherwise than by the terms of the appended claims.

What is claimed is:

- 20 1. A through-wall flashing for masonry walls and the like comprising a metal flashing sheet of desired width to extend horizontally substantially through the wall, said flashing sheet having its surface thereof provided with raised elements the sides thereof being upwardly inclined and presenting mortar-engaging surfaces obliquely disposed at a substantial inclination with reference to a transverse axis through said wall and to each other, whereby upon hardening of a layer of mortar around said surfaces, a superposed course of masonry will be restrained from shifting transversely of said wall, and additional means for bonding the flashing and superposed masonry against vertical separation.
- 25 2. A through-wall flashing for masonry walls and the like comprising a metal flashing sheet of desired width to extend horizontally substantially through the wall, said flashing sheet having its surface thereof formed with upwardly inclined mortar-engaging surfaces presenting faces of substantial length inclined with respect to the side edge of said flashing sheet and to each other whereby upon hardening of a layer of mortar surrounding said surfaces, a superposed course of masonry will be restrained from shifting transversely of said wall and additional means for bonding the flashing and superposed masonry against vertical separation.
- 30 3. A through-wall flashing for masonry walls and the like comprising a metal flashing sheet of desired width to extend horizontally substantially through the wall, said flashing sheet having its surface thereof provided with a plurality of raised portions arranged transversely of the sheet,

the sides of said portions being upwardly inclined and presenting pairs of parallel mortar-engaging faces, certain of said faces being disposed obliquely to the longitudinal edge of said sheet and to each other whereby upon hardening of a layer of mortar surrounding said surfaces, a superposed course of masonry will be restrained from shifting transversely of said wall.

4. A through-wall flashing for masonry walls and the like comprising a metal flashing sheet of desired width to extend horizontally substantially through the wall, said flashing sheet having its surface thereof provided with a plurality of raised portions arranged transversely of the sheet, the sides of said portions being upwardly inclined and presenting pairs of parallel mortar-engaging faces, certain of said faces being disposed obliquely to the longitudinal edge of said sheet and to each other, and others of said faces being disposed transversely of said sheet, whereby upon hardening of a layer of mortar surrounding said surfaces, a superposed course of masonry will be restrained from shifting transversely of said wall.

5. A through-wall flashing for masonry walls and the like comprising a metal flashing sheet of desired width to extend horizontally substantially through the wall, said flashing sheet having its surface thereof provided with raised portions arranged transversely of the sheet, the sides of said raised portions including upwardly extending mortar-engaging surfaces, presenting parallel faces obliquely disposed with reference to the longitudinal edge of said sheet, said obliquely arranged faces being angularly disposed with reference to each other, the apices of one set being oppositely disposed to the apices of an adjacent set, whereby upon hardening of a layer of mortar laid upon the upper surface of said flashing sheet a superposed course of masonry will be restrained from shifting longitudinally and transversely of said wall.

6. A through-wall flashing for masonry walls and the like comprising a sheet of metal flashing material adapted to be embedded in a mortar joint of said wall, said flashing sheet being of sufficient width to extend substantially through said wall, the upper surface of said sheet being provided with a plurality of raised buttons, certain of the sides of said buttons being parallel with sides of others of said buttons, and being disposed obliquely to the longitudinal edge of the sheet and to each other, the obliquely disposed surfaces of said buttons being arranged to interlock with the layer of mortar which, upon hardening, will resist shifting of a superposed course of masonry transversely and longitudinally of said wall.

7. A through-wall flashing for masonry walls and the like comprising a transversely ribbed sheet of metal flashing adapted to be embedded in a mortar joint of said wall, said flashing sheet being of sufficient width to extend substantially through said wall, the upper surface of said sheet intermediate said ribs being provided with a plurality of raised buttons, certain of the sides of said buttons being parallel with sides of others of said buttons, and being disposed obliquely to the longitudinal edge of the sheet and to each other, the obliquely disposed surfaces of said buttons being arranged to interlock with the layer of mortar which, upon hardening, will resist shifting of a superposed course of masonry transversely and longitudinally of said wall.
